CLOSURE MEMBER FOR ELECTRIC DIS-
CHARGE TUBES AND THE LIKERobert M. Bowie, St. Marys, Pa., assignor to Hy-
grade Sylvania Corporation, Salem, Mass., a
corporation of Massachusetts

Application March 31, 1937, Serial No. 134,059

4 Claims. (Cl. 250—164)

This invention relates to closures for electric discharge tubes and more particularly to such devices of the vacuum or low pressure type.

The invention is in the nature of an improvement on the type of closure member disclosed in application Serial No. 82,742, filed June 1, 1936.

A principal object of the invention is to provide an electron discharge tube of the composite metal-glass evacuated envelope type having a 10 vitreous window or closure member which is supported around its periphery against atmospheric pressure, by a member which is not sealed into the said vitreous member.

A feature of the invention relates to an evacuated 15 envelope having its main body portion of metal which is sealed to a vitreous closure member by an intermediate ring or frame of metal, a portion of the envelope being provided with a peripheral seat or ridge to support the vitreous member against atmospheric pressure without 20 affecting the efficacy of the seal.

Another feature relates to the means for supporting a metal-framed vitreous closure member for the metal wall of an evacuated enclosing envelope, so that the frame can be welded or otherwise fastened to the metal wall without damaging 25 the seal between the frame and the vitreous member.

A further feature relates to an evacuated envelope having a main body portion of metal with 30 a relatively massive vitreous member at the end, the arrangement being such that the mechanical supporting of the vitreous member against atmospheric pressure is borne substantially entirely by end thrust of the vitreous member directly 35 against the end of the envelope. As a result of this feature the sealing ring or frame is used substantially entirely to effect a vacuum tight seal between the vitreous member and the metal envelope and therefore it may be of relatively thin 40 metal strip. Since the sealing strip must be of a special alloy the cost thereof is materially reduced while at the same time enabling a more reliable and satisfactory seal to be achieved. The 45 use of such thin metal strip for the sealing ring or frame has the pronounced advantage that if the vitreous member is sealed thereto by a press molding operation, as described for example in said application Serial No. 82,742, there is less 50 chance of a defective seal existing than is the case where the frame is of relatively heavy gauge sheet metal stock.

A still further feature relates to an improved 55 cathode ray tube of the composite metal-glass envelope type.

While the invention will be described herein as applied to a cathode ray tube such as is employed in television and similar receiving systems, it will be understood that the invention is equally well applicable to similar devices such as 5 radio tubes, light sensitive devices, oscillograph tubes for television or picture analysis, for example tubes known in the art as "iconoscopes", "dissector tubes" and the like. In fact the invention is applicable to any evacuated device in 10 which a vitreous closure member of large surface extent is required to be sealed in a vacuum tight manner to an enclosing envelope. Furthermore, merely for purposes of explanation, the invention will be disclosed as embodied in a cathode ray 15 tube of the rectangular end or window type, but it will be obvious that it is applicable to other shapes such as round, oval or the like. It will be understood that while the invention is illustrated in connection with a device having a window at 20 one end thereof, this window may be located at any other part of the device, for example in one of the side walls. Likewise only sufficient parts of the cathode ray tube structure are shown to enable the invention to be understood. Accord- 25 ingly in the drawing,

Fig. 1 is a longitudinal plan view, partly in section, of a cathode ray tube embodying the invention.

Fig. 2 is a left-hand end view of Fig. 1.

Fig. 3 is a sectional view of Fig. 1 taken along the line 3—3 thereof and viewed in the direction of the arrows.

Fig. 4 shows a modification of the invention.

Fig. 5 is another view of the modification of 35 Fig. 4.

Fig. 6 shows the invention embodied in a radio tube of the metal envelope type.

Fig. 7 is a modification of Fig. 6.

Referring to Fig. 1, there is shown partly in 40 section and partly in dotted outline, a typical cathode ray tube comprising an elongated neck portion 1 of glass or other suitable material. The main body 2 of the tube is in the form of a frustum of a cone of a suitable metal such for 45 example as steel. In order to insure a vacuum-tight seal between the portions 1 and 2 there is provided a special sealing ring 3 of an alloy which has substantially the same coefficient of expansion as the glass 1. Preferably the flare 4 50 of the neck is of "Corning 705AJ" glass and the ring 3 is of "kovar", an alloy consisting of approximately 18% cobalt, 28% nickel and 54% iron. While any known manner of effecting the union between members 3 and 4 may be em- 55

ployed, it is preferred to employ the method as described in detail in application Serial No. 99,384, filed September 4, 1936. It will be understood of course that any well-known form of 5 "electron gun" and associated electrodes such as a control electrode, electron beam focussing means, main and auxiliary anodes, and the like are mounted within the neck and suitable beam deflecting means are also provided. For a detailed description of a typical electrode structure reference may be had to application Serial 10 No. 95,970, filed August 14, 1936.

As shown clearly in Fig. 1, the metal body portion 2 is welded or otherwise hermetically 15 fastened to the ring 3, and said body portion terminates at its enlarged open end in a flange comprising a shoulder 5 and a rim 6, the latter preferably, although not necessarily, extending at right angles to the longitudinal axis of the tube. The 20 enlarged end of the tube body 2 is closed by means of a relatively massive rectangular transparent vitreous member 7 of such dimensions that it fits snugly in the shoulder 5, and for this purpose 25 preferably the said member 7 is provided with a rim 8 where it contacts with the shoulder 5.

In order to provide a vacuum-tight seal between the closure member and the tube proper the said closure member has sealed into and around the edge thereof a metal frame 9 having 30 an integral flat rim 10 joined thereto by a curved portion 11. The rim 10 preferably extends parallel to the member 7 and is dimensioned so that when the rim 8 is in contact with shoulder 5, the parts 6 and 10 are likewise in contact. In 35 other words, the weight of the member 7 is borne substantially entirely by the shoulder 5. It will be understood of course that the inner surface of member 7 is provided with a suitable coating of material or materials which become fluorescent when struck by the electron beam, as indicated by the stippling in Fig. 3. When the member 7 has been positioned on the end of the tube the parts 6 and 10 may be hermetically sealed as 40 by welding, brazing and the like and thereafter the tube may be evacuated and processed in the 45 manner well-known in the electron tube art.

I have found that with the particular manner of supporting the member 7 as described, it is possible to use relatively thin metal strip stock 50 for the frame 9 since this frame is employed merely to provide a vacuum tight seal between the rim 6 and the glass 7. Heretofore it has been proposed to employ relatively heavy gauge metal sheet for the frame 9 since this frame was required not only to effect the necessary vacuum-tight seal but also to carry the entire weight of 55 the member 7 and also the force of the atmospheric pressure on said member. Apart from the difficulty of welding a relatively massive metal frame to the rim 6, there was always the possibility that during the welding of the parts 6 and 10, the seal between the glass 7 and the frame 9 might be destroyed. I have found that the use 60 of light gauge metal strip for the frame as is rendered possible by the present disclosure, not only facilitates the welding of the parts 6 and 10 but also reduces the chance of destroying the seal.

In addition to the advantages of providing a more reliable seal is the economic advantage that 70 considerably less material is required for the frame 9. When it is considered that a special alloy must be used for the said frame it once becomes apparent that the segregating of the sealing and mechanical supporting functions of the frame as above described, very materially re-

duces the cost of the finished tube. For example with the arrangement as described I have found it possible to employ for the frame 9, "kovar" of the order of 0.0075 inch in thickness, whereas to produce a satisfactory seal with the prior 5 method it was necessary to use an alloy of the order of 0.03 inch in thickness.

In addition to improving the seal and reducing the cost of assembling the tube, the use of the thin gauge metal frame also reduces the cost of sealing in the said frame to the glass 7. This is particularly true where the frame 9 is sealed into the glass 7 by a pressure molding operation such for example as disclosed in said application Serial No. 82,742. When relatively heavy gauge metal strip is employed in the frame, as a result of the sealing in process it is necessary carefully to anneal the frame and the seal area so as to avoid warping of the glass due possibly to slight differences in the rates of cooling of the glass 20 and metal, or to avoid distortion of the frame. This annealing operation not only increased the cost and time of manufacturing the framed window, but also increased the percentage of defective seals and defective windows. I have 25 found that by mechanically supporting the window 7 on the shoulder 5, against atmospheric pressure, enabling the use of the thin gauge metal for the frame, the costly annealing operation referred to is obviated or at least the same 30 degree of care and control is not necessary when sealing the frame 9 into the glass 7. The above noted disadvantages of the prior tubes made with heavy gauge metal for the frame 9 are particularly noticeable when the window is non-circular 35 in shape. For example in the case of rectangular windows as shown in the drawing, the use of heavy gauge metal for the frame very frequently caused the glass to crack, particularly at the corners, during the seam welding of the parts 6 and 10. If with the prior construction the frame 40 9 were made sufficiently thin to avoid this cracking during the seam welding, it would then be too thin to support the window against the atmospheric pressure on the outside thereof.

Preferably, in order to avoid trapping of air 45 between the contacting surfaces of the rim 8 and shoulder 5 during the evacuation of the tube, the said rim 9 is provided with one or more grooves 50 12. It will be obvious however that instead of providing these grooves in the rim 9, the shoulder 5 where it contacts with the rim 9 may be grooved or corrugated to avoid this trapping of air.

While the drawing shows the window 7 supported on the shoulder 5 throughout its entire 55 periphery, it will be understood that this is not necessary. Thus there is shown in Figs. 4 and 5 an arrangement wherein the window 7 is spaced throughout the major portion of its periphery from the shoulder 5. In this embodiment the 60 corners of the shoulder 5 are provided, with projections 13 such for example as embossings or the like, to engage and support the window 7. With the arrangement of Fig. 4, therefore the window is out of contact with the member 2 except at the points of support 13. Instead of providing the spacing and supporting lugs on the shoulder 5, these lugs may be formed as integral 65 projections from the corners of the glass 7. Various other manners of supporting the window against the end of the tube portion 2 will be clear from the foregoing descriptions of typical embodiments.

While the invention has been described as applied to cathode ray tubes it is also applicable to 70 75

electron discharge tubes such as radio tubes, light-sensitive cells, and the like. Thus there is shown in Fig. 6 a typical radio tube comprising an enclosing envelope 15 of a metal such as steel or other metal ordinarily employed in "metal" radio tubes. The envelope 15 is provided with a flange comprising the shoulder 16 and the flat rim 17. Adapted to be seated against the shoulder 16 is a closure member 18 of glass or other suitable insulating material such as ceramic or the like and into which are sealed in a vacuum-tight manner the wire prongs 19. Suitably supported from the member 18 and within the envelope 15 is any well-known form of radio tube mount indicated generally by the numeral 20, it being understood that this mount may be insulatingly spaced at its upper end from the metal wall 15. In order to seal the member 18 to the member 15 in a vacuum-tight manner, the said member 18 has sealed therein around the edge thereof a thin metal ring or frame 21 corresponding to the frame 9 of Fig. 1, it being understood that the ring 21 is of a suitable metal capable of being sealed in a vacuum-tight manner to the member 18, and having substantially the same coefficient of expansion as said member 18. The member 18 carrying the ring 21 and the electrode mount is assembled against the end of tube 15 and the flat rim 22 is seam welded to the rim 17. The tube may thereupon be evacuated through the exhaust tubulation in the well-known manner, after which this tubulation may be sealed off as indicated by the numeral 23.

Instead of providing the rims 17 and 22 extending outwardly relatively to the vertical axis of the tube, these rims may be turned downwardly as indicated in Fig. 7. Various changes and modifications may be made without departing from the spirit and scope of the invention. By the expression "permanently evacuated" as employed in the claims is meant a device such as a cathode-ray tube which has been evacuated and has been permanently sealed-off, to distinguish from an arrangement where the parts are not sealed together in a vacuum-tight manner and require evacuation during the operation of the device.

What I claim is:

1. An electron discharge tube having a body portion in the form of a metal tube, a flange at the end of said body portion defining a peripheral seat, a vitreous closure member for said tube said closure member being supported from said flange by a plurality of spaced projections, a metal frame sealed in a vacuum-tight manner into and around said closure member, said frame being fastened to the end of said tube in a vacuum-tight manner. 5

2. A cathode ray tube having a glass neck joined to a flared metal tubular member, a vitreous plate closing off the enlarged end of said tubular member, a peripheral shoulder in said enlarged end to receive said plate, a thin metal frame sealed into and around the edge of said plate, said frame being welded to the flared end of said tubular member. 10 15

3. A cathode ray tube comprising a glass neck sealed to a flared metal body portion, a flange at the end of said body portion and extending substantially perpendicularly to the axis thereof, a peripheral seat in said flange, a relatively massive vitreous plate conforming in shape to said seat and lying thereon, a thin metal frame sealed into the edge of said plate and having a flange extending parallel to the first-mentioned flange, both of said flanges being fastened together in a vacuum-tight manner. 20 25

4. An electron discharge tube having a metal tubular body portion, a peripheral flange at one end of said body portion and provided with a peripheral shouldered recess, an insulating closure member in the form of a substantially flat glass member lying in said recess, said recess receiving substantially the entire thrust of said glass member under outside atmospheric pressure, a plurality of lead-in wires sealed directly through said glass member, an electrode mount supported from said closure member within said tubular body, a thin metal frame having one peripheral margin sealed directly in a vacuum-tight manner into and around the margin of said glass member and its other peripheral margin sealed directly to the peripheral flange on said body portion. 30 35 40 45

ROBERT M. BOWIE.
